E. ANTINORO

MULTIPLE SAFETY FUSE

Filed June 15, 1921

UNITED STATES PATENT OFFICE.

EDUARDO ANTINORO, OF ROME, ITALY, ASSIGNOR TO THE COMPANY MARIO GOBBO,
LIQUIDATOR OF THE SOCIETÀ ANONIMA F. I. V. E. R., OF FLORENCE, ITALY.

MULTIPLE SAFETY FUSE.

Application filed June 15, 1921. Serial No. 477,742.

To all whom it may concern:

Be it known that I, EDUARDO ANTINORO, a subject of the King of Italy, and residing at Rome, Italy, whose post-office address is, 5 Via Mecenate 95, Rome, Italy, have invented certain new and useful Improvements in Multiple Safety Fuses, of which the following is a specification.

This invention relates to improvements in 10 and modifications of the multiple safety fuse described in patent application No. 363,041 of March 3rd, 1920. In the construction disclosed in said prior application, the contacts are disposed on the bottom of the safety 15 box, in an angular position, corresponding to the number of wires, comprising the circuit to be protected. The improvements and modification according to the present invention consists in the contacts being placed 20 both on the bottom and cover of the safety box, by which the construction of the device becomes simpler and more compact. A further modification and improvement resides in the rotatable plug containing longitudinal passageways provided at their 25 ends with protecting covers of metal, so that the changing of molten fuse wires may be expeditiously accomplished without difficulty. Each of the metal covers contains a 30 central aperture for the introduction of fuse wires that is provided with a conical recess adapted to guide the point of the wire into the passageway.

The invention is illustrated in the accompanying drawings in which:

Figures 1 to 5 represent a fuse for monopolar or multipolar circuits. In said drawings, Fig. 1 is a front view of a fuse box.

Fig. 2 is a top plan view of the same. 40 Fig. 3 is a cross section on the lines 1, 2, 3, 4, 5 and 6 of Fig. 1.

Fig. 4 is a posterior view of the box shown in Fig. 2.

Fig. 5 is a plan view of the inner face of the cover.

In the embodiment of the invention shown in the drawings, the rotatable plug is a solid body A preferably of cylindrical shape and having parallel holes b arranged near its periphery and extending in the direction of its axis. These holes b are adapted to receive the fuse wires c, and the outer ends of the holes are enlarged to receive hollow metallic terminals d, which are connected to the plug A and to the wires c by means of

screws e. The outer ends of the terminals d are provided with recesses f adapted to receive the buttons g arranged at the ends of contacts h², h³ and p. The contacts h² and h³ are carried by current conveying strips 60 h' and h, and the outer ends i of these strips are provided with holes to receive the screws employed in connecting the conducting wires to said strips. Other conducting strips l are arranged along the inner face 65 of the wall of the casing and their rear ends are bent at right angles as shown at m in order to receive the screws employed in connecting the current conducting wires to the strips l. The ends i and m of said 70 strips are arranged in recesses provided in the back of the casing.

The parts n of the strips l are bent at right angles to the intermediate portions of said strips and rest on the front edge of the 75 casing, so that they may contact with current conducting strips o, o' carried by the cover. Said strips o, o' are connected to the contacts p, p.

After closing the box by means of the 80 nuts g, contacts h², and h³ and p possess sufficient resiliency to permit intermittent rotation of the plug A.

It will be noted that the inner end of the 85 bore of each tubular terminal d is of substantially frusto-conical shape to facilitate the threading of the wire c into the terminal.

From the foregoing it is believed that the 90 construction and arrangement of parts may be readily understood and it is obvious that 95 changes may be made in the details disclosed without departing from the spirit of the invention as expressed in the claims.

What is claimed and desired to be secured by Letters-Patent is:—

1. A multiple safety fuse for electric circuits comprising a casing, a rotatable plug arranged in said casing and provided with a plurality of longitudinal extending openings therein, fusible wires passing through 100 said openings, contact terminals secured to the plug, and connected to the opposite ends of said wires, and resilient contact members carried by the bottom and cover of said casing in position to contact with a plurality 105 of said terminals, the contacts in the bottom and cover of said box being disposed in angular positions, corresponding to the number of pole lines to be protected.

2. A multiple safety fuse including a 110

- closed casing, a rotatable plug arranged in the casing and formed of insulating material, said plug being provided with a series of apertures arranged around and parallel to its axis, hollow metal terminals arranged in the ends of the apertures, wires extending through said apertures and having their ends anchored in said terminals, contacts arranged on the top and bottom of said casing and provided with buttons adapted to engage said terminals, conductor strips connected with said contacts and having their ends extending to the exterior of said bottom, and electric conducting wires connected to said strips.
3. A multiple safety fuse including a closed casing, a rotatable plug formed of insulating material, arranged in the casing and having a handle projecting to the exterior of the casing, said plug being provided with a circular series of apertures arranged around and parallel to its axis, hollow terminals of conducting material arranged at the ends of the apertures, fusible wires extending through said apertures and having their ends anchored in said terminals, contacts arranged on the top and bottom of said casing and provided with buttons arranged to engage said terminals, conductor strips

connected with said contacts and having 30 their ends extending to the exterior of the casing, and electric conducting wires connected to said strips.

4. A multiple safety fuse including a casing consisting of a bottom, top and an endless wall, a rotatable plug of insulating material arranged in the casing and having a handle projecting through the top, said plug being provided with a series of apertures arranged around and parallel to its axis, hollow metal terminals arranged at the ends of the apertures, fusible wires extending through said apertures and having their ends anchored in said terminals, contacts arranged on the top and bottom of said casing 45 and provided with buttons adapted to engage said terminals, conductor strips arranged in the casing, connected to said contacts and having their ends extending to the exterior of said bottom, and electric conducting wires connected to said strip.

In testimony whereof I have hereunto signed my name in the presence of two witnesses.

EDUARDO ANTINORO.
